Application May 16, 1944, Serial No. 535,868

2 Claims. (Cl. 230—127)

1

My present invention relates to centrifugal blowers or pumps, and more particularly to a novel blower for obtaining a low air flow output with high efficiency.

An object of my invention is to provide a novel impeller means.

Another object of my invention is to provide a blower having a shrouded impeller of novel design and rotatable in a housing with a scroll type diffuser.

Another object of my invention is to provide a novel self-contained motor driven unit for providing proper airflow for supplying combustion air for gasoline heater operation, or similar applications, where a low air flow output is desired at high driving motor efficiency.

Another object of my invention is to provide a compact blower unit of great efficiency in comparison to its size and of such simplicity in construction as to adapt it for manufacture and installation at low cost.

The above and further objects and novel features of this invention will more fully appear from the following detailed description and the accompanying drawings wherein like reference characters refer to like parts in the several views. It is to be expressly understood, however, that the drawings are for the purpose of illustration only and are not designed as a definition of the limits of the invention, reference being had for this purpose to the appended claims.

In the drawings:

Figure 1 is a side view of a blower embodying my invention.

Figure 2 is a perspective view of my novel rotary impeller.

Figure 3 is a plan view of a blower embodying my invention with part of the casing broken away so as to better illustrate the structure of my novel impeller means.

Figure 4 is a sectional view of Figure 3 taken along the lines 4—4 and looking in the direction of the arrows.

Referring to the drawings, there is provided a casing 1 in which is mounted an electric motor indicated generally by the numeral 2. The motor 2 is of conventional structure and includes a stator 3 and rotor 4 having a commutator 5 on which rides suitable brushes, one of which is shown at Figure 4 in dotted lines and indicated by the numeral 6. The motor 2 has provided electrical connections leading from it to a plug 7 mounted on the casing 1 and arranged for connecting the motor terminals to a suitable source of electrical energy.

As shown in Figure 4 the rotor 4 has a shaft 8 projecting axially from one end thereof and rotatably mounted in a suitable anti-friction bearing 9 supported at the closed end of the casing 1. A second shaft 10 projects axially from

2

the opposite end of the rotor 4 and through the opposite end of the casing 1.

The opposite end of the casing 1 has provided around the outer edge thereof an annular shoulder portion 11 adapted to fit within an annular flange 12 of a casting indicated generally by the numeral 13. Suitable fastening means, as indicated at 14, are provided for securing the motor casing 1 to the casting 13.

10 The casting 13 includes an annular plate member 15 having provided at one side thereof the annular flange 12 and a sleeve member 16 positioned within the annular flange 12 and concentric therewith.

Positioned within the sleeve member 16 is a suitable anti-friction bearing 17 held in place in the sleeve 16 by an annular plate 18 fastened to the free end of the sleeve 16 by bolts 19. The shaft 10 projects through the bearing 17 and sleeve 16 and is rotatably mounted in the anti-friction bearing 17.

The plate 15 of casting 13 forms with a second plate 20 a housing indicated generally by the numeral 21. The plates 15 and 20 are bolted together by suitable bolts 22. The plates 15 and 20 are formed with suitable cooperating recesses so as to provide within the housing 21 a rotor chamber 23 surrounded by a scroll type diffusion chamber 24 open to the rotor chamber through a radial channel 25. The diffusion chamber 24 has provided an outlet opening 26 as will be explained.

Rotatably mounted in the rotor chamber 23 is my novel shroud type impeller indicated generally by the numeral 27 and formed by two annular plates 28 and 29 which are fastened together by suitable rivets 30.

40 The plate 29 has provided a frusto-conical shaped hub 31 which projects through an annular orifice 32 formed in the plate 28 and in spaced relation to the orifice defining surface of the plate 28.

The hub 31 is keyed at 33 to the end of the shaft 10 and held in place by a nut 34 which engages suitable screw threads at the end of the shaft 10.

45 Cooperating with the annular opening 32 provided in the plate 28 is a similar formed annular recess 35 surrounding in spaced relation the hub 31 of plate 29.

50 Radiating from the annular opening or pocket thus formed in the impeller 27 are annular shaped air impeller conduits or passages 37 formed by suitable cooperating recesses provided 55 in the opposite halves 28 and 29 of the impeller rotor 27.

The impeller conduits 37 extend radially from the annular orifice surrounding the hub 31 at the center of the impeller rotor 27 and such conduits 37 open at the circumferential edge of the impeller rotor 27. The conduits 37 are prefer-

ably formed of equal diameter throughout their length and open directly into the diffusion chamber 24, through the passage 25.

Provided in the plate 20 of the housing 21 is an annular opening 38 which is arranged to cooperate with the annular opening 32 of the rotor 27, as an air inlet.

The surfaces defining the openings 32, 35, and 38 are so formed that the area normal to the air stream progressively decreases so as to smoothly accelerate the air flow into the passages 37 radiating from the annular opening 32-35.

Surrounding the inlet opening 38 is an annular flange 39 which projects from the plate 20 and has provided therein a removable screen 40 held in place upon a shoulder 41 by a suitable snap ring 42.

A flange 43 formed integral with the plate 16 is provided for mounting the mechanism while a second flange 44 is provided for fastening the outlet 26 to a suitable conductor.

In operation it will be readily seen that the electric motor 4 will drive the impeller rotor 27, through the driving shaft 10 in a clockwise direction as shown in Figure 3, causing air to be drawn into the rotating impeller rotor 27 through the annular orifice or pocket 32, 35 and 38, whereupon the air stream under centrifugal force will be radially directed outward through the annular passages 37 into the scroll-like passage 24 and out the outlet opening 26.

It will be readily seen that such annular shaped conduits approach the ideal shape for efficient operation, since all the dimensions of the air flow passages 37 remain equal and there is not effected an expansion in one direction and a contraction in an opposite direction of the fluid medium due to one dimension diverging while another dimension converges, as in prior art devices.

It will be readily seen that for the same compression ratio and driving speed, the heretofore known impellers of the same diameter in order to accomplish equally low air flows would have to have impeller blades extremely thin in width, since the area of the passages at the impeller periphery is the main factor governing the efficient flow rate for any particular impeller. The width of such impellers would in fact be so small that frictional losses would be prohibitive. However, through use of my novel impeller rotor such frictional losses may be avoided.

Although only one embodiment of the invention has been illustrated and described, various changes in the form and relative arrangement of the parts, which will now appear to those skilled in the art, may be made without departing from the scope of the invention. Reference is, therefore, to be had to the appended claims for a definition of the limits of the invention.

What is claimed is:

1. A device of the character described, comprising, in combination, a two part circular rotor, a hub portion formed on one of said parts, said hub portion surrounded by an annular pocket formed in said one part, an annular orifice formed in the other part of said two part rotor, said hub portion projecting through said annular orifice, said first and second parts of said rotor having recessed portions cooperating to form a plurality of passages radially extending from said pocket and annular orifice, the passages opening at the circumferential edge of said circular rotor, means fastening the parts of said two part rotor together, a housing having a first and a second part for enclosing said

rotor, said first and second housing parts having recessed portions forming a scroll type diffusion chamber into which the passages of said rotor open, means for fastening said first and second housing parts together, a driving shaft affixed to said hub portion for rotatably mounting said rotor within said housing, and an annular air inlet opening passing through one part of said housing into said rotor opening, the surfaces defining the inlet and rotor openings being so formed that the area normal to the air stream progressively decreases so as to smoothly accelerate the air flow to said impeller passages through said air inlet, an annular flange projecting outwardly from the one part of said housing and surrounding said annular air inlet opening, and a screen mounted in said flange through which the air may be drawn directly from the atmosphere.

2. A centrifugal blower unit comprising, in combination, a two piece circular shaped impeller formed of first and second circular shaped plates, a hub projecting from the first plate, an annular pocket surrounding said hub and provided in the first plate, the second of said plates having an annular orifice through which said hub projects, said first and second plates having recessed portions provided therein cooperating to form a plurality of passages radially extending from said pocket and annular orifice, each of said passages having an inner surface defining the same of circular shape and equal diameter throughout the length of said passage, means fastening said first and second impeller plates together, the passages opening at the circumferential edge of said circular impeller, a housing formed of first and second plates for enclosing the impeller, said first and second housing plates having provided therein first cooperating recesses for receiving the impeller, second cooperating recesses for providing a scroll type diffusion chamber and third cooperating recesses for opening said scroll type diffusion chamber to the openings from said impeller passages, said first and second housing plates having formed therein an outlet opening for said diffusion chamber, means for fastening said first and second housing plates together, the first of said housing plates having an air inlet opening provided therein for cooperating with the annular orifice and pocket provided in said impeller so as to supply air to said impeller, the surfaces defining the inlet opening, annular orifice and pocket being so formed that the area normal to the air stream progressively decreases so as to smoothly accelerate the air flow to said impeller passages through said air inlet, an annular flange projecting outwardly from the first housing plate and surrounding said air inlet opening, and a screen mounted in said flange through which the air may be drawn directly from the atmosphere, a bearing provided in said second housing plate, an annular flange projecting from said second housing plate, a motor supported by said flange, a shaft driven by said motor and rotatably mounted in said bearing, said shaft drivingly connected to said impeller and rotatably supporting said impeller within said housing, whereby upon rotation of said impeller the fluid medium under centrifugal force will be directed from the openings of the passages of said impeller into said diffusion chamber and out the outlet from said diffusion chamber.
